FIG. 4

FIG. 6

BY

INVENTOR.
Walter J. Rice
Cornelia L. E. Rice
ATTORNEY.

UNITED STATES PATENT OFFICE.

WALTER J. RICE, OF PHILADELPHIA, PENNSYLVANIA.

MARBLE GAME.

Application filed December 10, 1927. Serial No. 239,124.

My invention relates to game apparatus, and more particularly, to apparatus for playing a game simulating baseball.

In accordance with my invention, a small body, as a marble, or the like, is rolled or pitched along an alley or runway at or near the end of which is disposed a plurality of indicators, of various widths, and preferably spaced at varying distances from each other, each having thereon a legend which determines the value of the indicator when moved or displaced by the marble, and a portion of a legend the remainder of which is on an adjacent indicator to determine the value of both when simultaneously moved or displaced by the marble.

Further in accordance with my invention there is provided a score board having thereon a miniature representation of a baseball diamond, markers or counters being placed in positions determined by displaced indicators thereon to disclose the progress of the game and the status of a player or team of players at any instant during a period or inning of the game to enable the player or team to utilize his or their knowledge and skill in view of the revealed situation and of the known hazards of the game due to the various widths and markings or legends of the indicators.

My invention further resides in features of construction and combination hereinafter described and claimed.

For a disclosure of one form of my invention, reference is to be had to the accompanying drawing, in which:

Fig. 1 is a plan view of the game board constructed in accordance with my invention.

Fig. 2 is an elevational view, partly in section, and on an enlarged scale, taken on line 2-2 of Fig. 1.

Fig. 3 is a side elevational view, in section, and on an enlarged scale, taken on line 3-3 of Fig. 1.

Fig. 4 is a plan view of a score board utilized in connection with the board of Fig. 1.

Figs. 5 and 6 show a modification of the indicating member in two stages of construction.

Referring to Figs. 1 to 3, between the side frames 1, 1 there is positioned the horizontally extending base member or board 2 having one end terminating substantially flush with the forward or players' end of the

side frames and its opposite end ending at a desired distance from the other or indicator end of the frames. The base board 2 is secured in any suitable manner, as by adhesive, intermediate the width of the side frames, the upper portions 1^a of which constitute guard structure to prevent a marble or the like, propelled along the baseboard, from going out of bounds defined by the board, and the lower portions 1^b of which constitute a support for the device. At a suitable distance from the front or players' end of the game apparatus, there is marked on the upper face of the baseboard 2, or printed on a covering as of paper fastened thereto, a "shooting line" 3 from which, at any point thereon, the players may suitably propel marbles or their equivalent. On the same face of the board, at a desired distance from the line 3 and between line 3 and the indicator end of the board, there is marked or printed a miniature representation of a baseball diamond 4 having a line 5 extending transversely thereof normal to the side frames 1.

At the indicator end of the board, the end piece 6 is fastened to the side frames 1 and to a bottom piece 7 which may, as shown, extend but a relatively short distance towards the opposite or players' end of the board. A supporting or bracing member 8, extending between and fastened to the side frames, is disposed between and secured to the lower side of the baseboard and to the upper side of the bottom 8. Other bracing or supporting members, such as cross pieces 9, 10, fastened to the side frames, maintain the surface of the base-board in the same plane, that is, prevent warping, sagging and other distortions by being secured to the under surface of the board. The cross pieces may be, as indicated, of sufficient width to engage the surface, as of a table, on which the game is placed.

Within the space between the end of the baseboard secured to block 8 and the end piece 6, are positioned a plurality of indicators 11 of various widths, and spaced at varying distances from each other across the width of the board 2. The indicators may be of any suitable composition, as wood or metal, and may be, as shown, pivotally mounted on a rod or bar 12 extending between the side frames and held in place as by a nut 13 threadably engaging one end thereof, the other end being provided with

a head 14. Spacing washers 15 on bar 12 between adjacent indicators 11 prevent longitudinal displacement of the individual indicators and maintain the proper space relation of adjacent indicators.

On the face of each indicator visible from the players' end of the board is painted, marked, printed, or the like, a legend which indicates the reward or penalty to be awarded or imposed as a result of the movement or displacement of the particular indicator by a propelled marble. There is also marked on the face of each indicator a portion of one or two legends, depending upon the position 10 of the indicator in the series, the remainder of which is on an adjacent indicator, which indicates the reward or penalty to be awarded or imposed as a result of the simultaneous displacement of two contiguous indicators.

In place of the spacing washers shown in Fig. 1, the indicators may have such spacing members formed integrally therewith in the manner shown in Figs. 5 and 6, wherein a 25 sheet metal blank or the like, 17, has side tabs 18 adapted to be formed to serve both as spacing and bearing members.

The indicators, though preferably, are not necessarily pivoted to the housing structure 30 and may be placed loosely on the base member. The present construction, however, is advantageous in that the indicators are supported below the level brought up to the aligning position against the edge of said base as shown in Fig. 3.

In playing the game, it is convenient to adopt the rules covering the game of organized baseball. Two teams, each consisting of one or more players, are alternately 40 entitled to shoot at the indicators until three "outs" have been made, until a specified number of "innings" have been played. To be counted as an attempt, the marble must cross the line 5 of the diamond 4, the player having the opportunity of recovering it before it passes that limit in the event of the marble 45 slipping. It is to be understood that the marble must be shot or pitched on or in front of the "shooting line" 3.

50 The score board 16 is for the purpose of marking the progress of the game and particularly to advise the team "at bat", or shooting at the indicators, of the situation at any given instant in order to permit the exercise of judgment, of skill, and of knowledge of the game of baseball in view of the known hazards of the game due to the width, spacing and marking of the indicators. For

example, at the beginning of the game or of each "inning", the marble is pitched until an "out" indicator has been hit, three "strike" indicators displaced, or a base hit indicator moved. In the first two instances, a marker is placed in the proper circle of the "out" column of the team "at bat", intermediate 60 balls and strikes being previously indicated by placing markers on the proper circles on the score board. In the latter instance, a marker is positioned on the proper base of the diamond marked in the score board, indicating that an imaginary batter has become 65 a base runner.

The shooting is then continued and the base runner is either advanced by other base hits or bases on balls, or he "dies" on the 70 bases, due to three outs before he has scored.

Further explanation is considered unnecessary in view of the well known rules of organized baseball which are followed in the 75 present game.

What I claim is:

1. In a game apparatus, a base member, a plurality of indicators movable with respect thereto, said indicators having a plurality of characters thereon representing the component parts of a game, some of said characters being complete and others incomplete with reference to an individual indicator.

2. In a game apparatus, a base member, a plurality of indicators varying in width pivoted with respect thereto, means for moving said indicators individually or in pairs about their pivots, and characters representing the component parts of a game so arranged on said indicators that said means may move one complete character when actuating a pair of said indicators simultaneously, and other characters when said indicators are actuated individually.

3. In a game apparatus, a base member, a plurality of indicators movable with respect thereto and arranged for variable spacing with respect to each other, said indicators having characters thereon representing the component parts of a game and adapted to be moved either singly or in pairs by operating means whereby characters are indicated to denote a play or part of said game.

4. In a game apparatus, a base member, a plurality of indicators movable with respect thereto and adapted to be variably spaced with respect to each other, said indicators being limited in movement in one direction by an edge of said base member.

WALTER J. RICE.
